UNITED STATES PATENT OFFICE.

IMMANUEL PFEIFFER, JR., OF BEDFORD, MASSACHUSETTS.

PINCERS.

1,134,980.

Specification of Letters Patent. Patented Apr. 6, 1915.

Application filed September 29, 1914. Serial No. 864,151.

To all whom it may concern:

Be it known that I, IMMANUEL PFEIFFER, Jr., of Bedford, in the county of Middlesex and State of Massachusetts, have invented 5 certain new and useful Improvements in Pincers, of which the following is a specification.

This invention relates to hand tools or implements of the type commonly known as pincers or pliers, and refers especially to 10 such implements having means for holding the jaws locked in adjusted or gripping positions.

In most implements of this character, the 15 locking devices are of a more or less pawl and ratchet or toothed segment type capable of holding the jaws only at either one of a plurality of predetermined relative positions, according to the spacing of the teeth 20 of the ratchet or segment, and such devices are ineffective when the article gripped by the jaws is of an intermediate size.

The object of my invention is to provide 25 an improved implement of this jaw type having locking means capable of securely holding the jaws from spreading, regardless of the size of the article grasped by the jaws.

To these ends my invention consists in 30 locking mechanism including a rotatively adjustable worm or spirally ribbed member carried by one member of the implement, to coöperate with suitable projections such as teeth of a segment, carried by the other member. With this structure I provide 35 means for rendering the locking devices inoperative to enable the implement to be employed in any ordinary manner.

Of the accompanying drawings, Figures 1 40 and 2 are respectively side and edge views illustrating my invention in one of its embodiments. Fig. 3 represents a section on line 3—3 of Fig. 1. Figs. 4 and 5 are views similar to Figs. 1 and 2, illustrating another 45 embodiment.

Similar reference characters indicate similar parts in all of the views.

Referring first to Figs. 1, 2 and 3, two members 12 and 13, pivotally connected at 50 14, are illustrated as having a well known jaw and handle shape. They may be of any well-known or preferred form usual for implements of this character. The member 12 is formed or provided with a toothed segment 55 15. The member 13 carries a worm 16 which, when engaged with the toothed seg-

ment, locks the two members against relative movement. The worm is fitted to rotate in an opening 17 in member 13 and has its journals or shaft 18 mounted in elongated bearings or slots 19. Intersecting each slot 19 substantially mid-way of its length, is a recess (Fig. 3) in which is mounted a spring-pressed stud 20 capable of yielding to permit the shaft 18 to be 60 shifted to either end of the slot 19 and held there. When the parts are in the position indicated by full lines, the implement is capable of use in the usual manner, the same as though no locking devices were present. The worm can, however, be instantly shifted to the dotted line position of Fig. 3, the shaft 18 depressing the two studs 20 which then snap back or upward to positively hold the worm with its spiral rib or 70 ribs interlocked with the teeth of the segment. Since any force tending to spread the jaws causes pressure of the teeth of the segment only against the side of the worm rib, and since the spiral is a low-pitched 75 one, such pressure cannot cause the worm to rotate. The worm can, however, be readily rotated by the fingers of the user to bring the proper portion of its rib or ribs into engagement with the toothed segment to cause 80 the jaws of the two members to be locked in close engagement with the article between the jaws, regardless of the exact size of such article.

Suppose the user has closed the jaws upon 85 an article and then desires to lock them. If, when the worm is shifted from the full line position of Fig. 3 toward the dotted line position, the worm rib fails to enter a space between the teeth of the segment, rotation of the worm in either direction will bring a portion of the rib opposite such space and the action of the springs under the studs 20 will cause the rounded tops of the studs to act as cams on the shaft 18 and 90 complete the movement of the worm to locking position.

While one side of the worm projects from the opening 17 sufficiently for ordinary convenience of manipulating it, I preferably 95 form the opening entirely through the member 13 and enlarge the lower portion thereof as indicated by dotted lines in Fig. 3.

When the worm is engaged with the toothed segment or segmental rack, and 100 then rotated, its spiral rib will act upon the teeth to cause the jaws of the pincers to open 110

or close to any extent desired, and will do this with such accuracy that the tips of the jaws or tips of the handles can be utilized as calipers.

5 Referring now to Figs. 4 and 5, it will be seen that the members 12 and 13 are substantially the same form as in the other figures, and the member 12 has a toothed segment 15 to coöperate with a worm 16 carried by member 13. Instead, however, of shifting the worm toward and from the segment to lock and unlock the members, the two members are themselves relatively adjustable to engage and disengage the worm and segment. The shaft 18 of the worm is mounted in cylindrical bearings instead of slots, and the member 12 is formed with a "key-hole" opening or slot 21 for the pivot stud 14. As usual with devices connected by stud and "key-hole" slot, the portion of the stud 14 which passes through the member 12 is flattened. This being a well-known connection the details need not be further described or illustrated herein. It is sufficient to explain that one member has a pivot stud capable of being shifted to either one of two bearings in the other member, which two bearings are at different distances from the toothed segment. When in the relative positions shown in Fig. 4, the pliers can be used as though no locking devices were present. By swinging the member 12 to the position indicated by dotted lines, it can be then shifted so that the flattened stud can slide through the narrow portion of the slot into the other bearing which is at the greater distance from the toothed segment, and then said member is swung back until the first tooth engages the worm, after which further swinging is controlled by rotating the worm. When the parts are in this condition, the closing and opening of the pliers is effected by rotating the worm, in a manner similar to the adjustment of a well-known type of "monkey wrench" having a screw that is shifted by the rotation of a nut. This form, like that of Figs. 1 and 2 will enable the tips of the jaws or the tips of the handles to be used as calipers, owing 50 to the fine adjustment obtainable by means of the worm.

It will be readily understood that the shiftable worm illustrated in Figs. 1, 2 and 3 may be used in connection with the shiftable pivot structure of Figs. 4 and 5. Referring to Figs. 4 and 5, it will be seen that in order to make the shift which results in engaging or disengaging the worm and segment, it is necessary that the two members 60 shall first be swung to or nearly to their

widest spread relationship. When the worm and segment are engaged, the gripping faces of the jaws can be brought to parallel but separated positions to conveniently grasp nuts. This is because, when the member 12 is shifted so that the pivot occupies the right hand end of the key-hole slot, the faces of the two jaws are spread a considerable distance apart although said faces are still parallel. This is a particular advantage of the form illustrated in Figs. 4 and 5. It will be now readily understood that if the worm shown in Figs. 4 and 5 is mounted in the manner shown in Figs. 1, 2 and 3, so that the worm can be shifted from and to the segment, it will not be always necessary to open the jaws wide before shifting the pivot to the left-hand end of the slot 21. In other words, by combining in one implement the structures illustrated in Figs. 1 and 4, the advantages of both forms will be possessed by a single implement.

I do not herein claim the specific structure illustrated in Figs. 1, 2 and 3, of mounting the worm so that it can be shifted to and from engagement with the toothed segment or rack, as the same forms the subject matter of another application filed by me March 11, 1915.

I claim:

1. An implement of the character described, comprising two members, one member having a toothed segment and the other having a worm to coöperate with the segment, said members having a shiftable pivot connection to permit engagement or disengagement of the toothed segment and worm.

2. An implement of the character described, comprising two members, one member having a toothed segment and the other having a worm to coöperate with the segment, one of said members having a key-hole slot and the other having a pivot member shiftable along said slot to permit engagement or disengagement of the toothed segment and worm.

3. An implement of the character described, comprising two members, one member having a key-hole slot and a toothed segment adjacent said slot, the other member having a pivot stud extending through said slot and having a worm to coöperate with the toothed segment.

In testimony whereof I have affixed my signature, in presence of two witnesses.

IMMANUEL PFEIFFER, JR.
